UNITED STATES PATENT OFFICE

ABRAHAM NOVICK, OF FLUSHING, NEW YORK, ASSIGNOR TO F. L. SMITH MACHINE CO., INC., OF NEW YORK, N. Y., A CORPORATION OF NEW YORK

SCORING MECHANISM FOR USE IN ENVELOPE MAKING MACHINES

Application filed March 21, 1929. Serial No. 348,749.

The present invention relates to machines for making envelopes from envelope blanks and more particularly to an improved scoring roll for use therein.

Among the objects to be attained may be mentioned an improved arrangement of the blades for producing the longitudinal and transverse scoring lines in the blanks, improved means for holding same so as to insure increased accuracy and ease of adjustment as well as to facilitate the removal and replacement of the parts, and improved guide means for the blanks for preventing them from adhering to the scoring rolls.

Other objects and advantages of my invention will be apparent as the description proceeds and the specific features of novelty will be pointed out in the appended claims.

The invention will be best understood by reference to the following detailed description taken with the accompanying drawings, in which:

Fig. 1 is a view in front elevation of an illustrative embodiment, parts being in section and broken away;

Fig. 2 is a detail of the spacer plate used and showing the manner of its attachment to the shaft;

Fig. 3 is a view on a reduced scale of the main shaft and showing a retaining groove in the same;

Fig. 4 is a view of the middle portion of the holder for the long transverse blades;

Fig. 5 is a view of one of a set of blades comprising a second scoring element;

Figs. 6, 7, 8 and 9 are views taken respectively along the lines 6—6, 7—7, 8—8, and 9—9 of Fig. 1;

Fig. 10 is a view in section through the spacer element; and

Fig. 11 is a diagrammatic showing of a plane development of the scoring blades and also of the blank to be scored.

The general arrangement of the scoring blades in the preferred embodiment is illustrated in Figure 11. Advantage is here taken of the fact that in an envelope blank of the type operated upon, the score lines intersect on the periphery of the blank whereby the scoring blades may extend beyond the points

of intersection of the score lines. As will be evident from Fig. 11, one of the transverse scoring blades extends the length of the longest score line for which the machine is adapted, while abutting this blade is a pair of circumferential blades which between them contain the second transverse blade which is of adjustable length.

The mechanism for carrying out this arrangement may now be described in detail.

Referring to Fig. 1, 10 denotes the shaft upon which the various elements are mounted, including a pair of collars 11, 12, between which the scoring blades are mounted; as will be best seen from Fig. 9, collar 12, for example, is splint and has adjacent portions held together by means of a set screw 12a by means of which the collar is firmly affixed to the shaft, the same construction obtaining in the case of collar 11. Collars 11 and 12 have attached thereto a transverse bar 14 of segmental shape and secured to said collars by means of screws 14—a, 14—b, one purpose of such bar being to constitute a feeding sector for the scoring roll. Attached to said feeding segment 14 is a pair of transverse scoring blades 16, 16 which together extend the length of the scoring roll. As will be seen from Fig. 1, each blade 16 abuts a pin 19 at the middle of bar 14, the purpose of which is to insure an exact spacing between said blades in order to accommodate the blank guiding member A, to be referred to hereafter. Bar 14 also has a circumferential slot 17 to accommodate guide member A. Each blade 16 is secured to said feeding sector 14 by means of bolts 20, 20 and 21, 21, Fig. 1. By means of the elements thus far recited, the long transverse scoring blades 16 are mounted upon the shaft 10.

Also adjustably mounted on shaft 10 are the circumferential scoring blades 22, 23, blade 22, for example, being mounted upon a collar 24 by means of retaining screws 25, 25, 25, collar 24 being split and secured to shaft 10 by means of a set screw 27. In this manner blade 22, for example, is adjustable angularly of the shaft and is at all times in position to abut transverse blade 16. The

same construction applies to circumferential blade 23.

The second transverse blade 30 is composed preferably of three elements, 30-a, 30-b, and 30-c, Figs. 1, 9, and 11, the arrangement being such that the straight edges of the blades are together whereby a scoring blade is formed either by the combination of two blades or by a single blade, reference being had to Figs. 6 to 9, inclusive. Blades 30-a, 30-b, 30-c are adjustably held in holder members 32 by means of set screws 33, Fig. 1. I also find it desirable to fix the holder members 32 angularly with respect to the shaft 10 by mounting same in a groove 35, Figs. 8 and 1, having its sides diverging inwardly, and in which a key 36 is mounted, and a screw 37 attached thereto. In this manner holder members 32 are adjustable longitudinally of the shaft 10 but cannot rotate with respect thereto. Also, by loosening set screws 33 the blades 30 are extensible as desired so as always to abut the circumferential blades 22, 23. Said blades are also provided with a slot 34 to accommodate the guide A. Means for insuring the registry of said slots and guide will be described below.

In the foregoing I have described the mounting of the pairs of transverse and circumferential scoring blades which upon plane development enclose a rectangle as seen in Fig. 11. I find it desirable to provide a spacer member 40 in the space enclosed by said blades in order to prevent the blanks from being caught therein, said member 40 being illustrated in Figs. 2 and 10 and comprising a split ring 41 held together by means of a set screw 42 threaded into enlargements 43 in said ring. Member 40 also comprises a fin or rib 45, Figs. 10 and 1, which is useful in serving as a means for locating the external slot 34 of blade 30-c in correct position owing to the fact that said rib registers with a slot 30-x in the inner edge of said blade which is directly in line with slot 34. Spacer member 40 itself is located on the shaft 10 by means of studs 46, 47, Fig. 2, secured to said shaft. I find it desirable to have the external face of the spacer member resiliently mounted, such face plate 48, Figs. 2 and 10, being held against lips 49 of said member by means of springs 52, 53, screws 50 and 51 serving as guides for said plate. Also said spacer member 40 is preferably fixed to shaft 10 by means of a key 55 in a groove 56 in said shaft whereby the spacer member cannot rotate with reference to the shaft.

Preferably I provide a plurality of spacer members 40 of different size for use with different spacing of the score blades.

Cooperating with the scoring roll thus far described is a counter roller 60 having thereon a resilient outer layer 61 against which the scoring blades adhere. To further insure the accurate disposition of the transverse

blade 16, I provide additional collars 62, 63, Fig. 1.

A feature of the invention is to provide positive guide means to insure that the envelope blanks will not ride up from the counter roller as by adhering to the scoring blades. To accomplish this I provide a guide member A disposed preferably so as to be above the median line of the envelope blank and which passes entirely through the roll pair comprising the scoring roll and the counter roll 60, it being noted that transverse blades 30, spacer member 40, transverse member 14 all containing a circumferential slot to accommodate this guide. Also provided adjacent to said rolls is a table 65 having portions which terminate close to roll 60 and which effectively prevent the blank from adhering to said roll. Guide A is supported from above the table 65 by means not shown.

It will be evident that by the means described in the foregoing, the envelope blanks may be quickly and correctly scored, and furthermore, without danger that the blanks be carried out of their course in the machine by adhering to either the scoring roll or the counter roll thereof. Furthermore, it will be evident that easy and positive means are provided for adjusting the blades for different sizes of blanks.

I wish it understood that various changes may be made in the specific embodiment described without departing from the spirit of the invention, and that parts thereof may be used without others.

I claim:

1. A scoring roll for a machine for making envelopes and the like, comprising a shaft, a pair of angularly separated transverse scoring blades, means for mounting same on said shaft permitting angular adjustment of said blades with respect to one another, a pair of circumferential blades, a mounting securing same to the shaft, both said circumferential blades abutting one and the same transverse blade and extending beyond said other transverse blade.

2. A scoring roll for a machine for making envelopes and the like, comprising a shaft, a pair of angularly separated transverse scoring blades, means for mounting same on said shaft permitting angular adjustment of said blades with respect to one another, a pair of circumferential blades, a mounting securing same to the shaft, both said circumferential blades abutting one and the same transverse blade and extending beyond said other transverse blade, said circumferential blades being adjustable along said shaft.

3. A scoring roll in accordance with claim 1, in which one of the transverse blades is fixed angularly with respect to the shaft.

4. A scoring roll for a machine for making envelopes and the like, said roll having

5 a shaft, a pair of transverse scoring blades mounted thereon, a pair of circumferential blades also mounted on said shaft, in combination with a counter roll adhering against said scoring roll and a guide member extending continuously between said rolls from one side thereof to the other and preventing the blanks from adhering thereto.

10 6. A scoring roll for a machine for making envelopes and the like, said roll having a shaft, a pair of transverse scoring blades mounted thereon, a pair of circumferential blades also mounted on said shaft, in combination with a counter roll adhering against 15 said scoring roll, a table along which the blanks are transported to and away from the said rolls, and a guide member disposed above said table, allowing the blanks to pass between same and said table and extending between said rolls from one side thereof to the other.

20 7. A scoring roll for a machine for making envelopes and the like, comprising a shaft, a pair of angularly separated transverse scoring blades, means for mounting same on said shaft permitting angular adjustment of said blades with respect to one another, a pair of circumferential blades, a mounting securing same to the shaft, said circumferential blades abutting one of said transverse blades and extending beyond said other transverse blade in combination with a counter roll adhering against said scoring roll and a guide member extending between said rolls preventing the blanks from adhering thereto, said transverse blades having a cutout portion to accommodate said guide member, and said mounting for said transverse blades including locating means comprising interfitting parts on said blades and said mounting respectively whereby said transverse blades when mounted will always be in position to avoid said guide member.

25 8. The combination in accordance with claim 6 in which said locating means comprises a rib on said mounting and a slot in said transverse blade.

30 9. A scoring roll in accordance with claim 1, in which the mounting for one of said transverse blades comprises a collar and means for adjustably holding same on said shaft.

35 10. A scoring roll for a machine for making envelopes and the like, said roll having a shaft, scoring blades mounted thereon, in combination with a counter roll adhering against said scoring roll, a table along which the blanks are transported to and away from the said rolls, and a guide member disposed above said table, allowing the blanks to pass between same and said table and extending continuously between said rolls from one side thereof to the other.

40 11. A scoring roll having a pair of transverse blades, a pair of circumferential blades,

said blades being so mounted that upon plane development they include a rectangle the corners of which occur upon the periphery of the blank to be scored, one of said transverse blades and both of said circumferential 70 blades extending beyond the periphery of the blank except for the largest blank which the roller is adapted to score, the other of said transverse blades being extensible so as to abut said longitudinal blades for any adjustment position, said arrangement of blades permitting the size of the rectangle to be varied in both directions.

12. A scoring roll having a pair of transverse blades, a pair of circumferential 80 blades, said blades being so mounted that upon plane development they include a rectangle the corners of which occur upon the periphery of the blank to be scored, one of said transverse blades and both of said circumferential blades extending beyond the periphery of the blank except for the largest blank which the roller is adapted to score, the other of said transverse blades being extensible and being contained within said circumferential blades which latter are non-extensible, said arrangement of blades permitting the size of the included rectangle to be varied in both directions. 90

13. A scoring roll for a machine for making envelopes and the like, said roll having a shaft, scoring blades mounted thereon, means disposed counter to said scoring roll and affording a surface against which the blanks are pressed by the scoring roll, a guide member disposed above said counter means allowing the blanks to pass between same and the scoring roll, said guide member passing between said roll and said counter means from one side thereof to the other. 105

14. A scoring roll for a machine for making envelopes and the like, comprising a shaft, a pair of angularly separated transverse scoring blades, means for mounting same on said shaft permitting angular adjustment of said blades with respect to one another, a pair of circumferential blades, a mounting securing same to the shaft, said circumferential blades abutting one of said transverse blades and extending beyond said other transverse blade, 110 115 120

15. A scoring roll for a machine for making envelopes and the like, comprising a shaft, a pair of angularly separated transverse scoring blades, means for mounting same on said shaft permitting angular adjustment of said blades with respect to one another, a pair of circumferential blades, a mounting securing same to the shaft, said circumferential blades abutting one of said transverse blades and extending beyond said other transverse blade, 130

said transverse blade against which the circumferential blades abut being of fixed length, and said other transverse blade being contained within said circumferential blades 5 and being extensible with the adjustment movement of said circumferential blades longitudinally of the shaft.

15. A scoring roll for a machine for making envelopes and the like, comprising a shaft, 10 a pair of angularly separated transverse scoring blades, means for mounting same on said shaft permitting angular adjustment of said blades with respect to one another, a pair of circumferential blades, a mounting 15. securing same to the shaft, said circumferential blades abutting one of said transverse blades and extending beyond said other transverse blade, and a spacer plate between said transverse blades and means for resiliently mounting same upon said shaft.

20. In testimony whereof I have affixed my signature to this specification.

ABRAHAM NOVICK.
